SAFETY APPLIANCE FOR SWITCHES

Filed July 23, 1928

INVENTOR
JOSEPH F. HADDOCK.

BY *Bruce S. Elliott*
ATTORNEY.

UNITED STATES PATENT OFFICE

JOSEPH F. HADDOCK, OF VALLEY PARK, MISSOURI

SAFETY APPLIANCE FOR SWITCHES

Application filed July 23, 1928. Serial No. 294,724.

This invention relates to railway switches, and has for its general object to provide a safety appliance which will prevent the switch point from being moved from an adjusted position, to either open or close the switch, should the switch-stand for any reason be accidentally destroyed or knocked over.

Such injury to the switch-stand is of not infrequent occurrence, and is usually caused by the door on a grain or other type of freight car breaking loose from its supporting brackets at the bottom and swinging outwardly from the side of the car and hitting the switch-stand as the train passes it. In this way, the switch point may be either moved to close the switch or in the opposite direction to open it, depending upon whether the switch-stand is hit by a train entering a siding or by one leaving a siding, with the result that the next train passing over the track will be derailed.

I am aware that attempts have been made to provide against such accidental operation of the switch, but so far as my knowledge extends, the only device that has found recognition is one which operates to hold the switch point against a rail of the main line. It is the object of my invention to provide means for preventing the accidental shifting of the switch either from its closed to its open position or from its open to its closed position.

With this object in view, my invention consists in the provision of novel manually-operable means for locking the switch in either of its adjusted positions, whereby if the switch-stand be accidentally knocked over or broken down by engagement of a swinging door of a freight train therewith, or from any other cause, the switch point will be prevented from being moved from the position it occupied when the accident to the switch-stand occurred.

Other objects and advantages of the invention will be apparent from the description of the invention to follow.

In the accompanying drawing—
50 Figure 1 is a plan view of my improved

safety appliance applied to a standard type of switch;

Figure 2 is a cross-sectional view on the line 2—2 of Fig. 1;

Figure 3 is a view in front elevation on 55 an enlarged scale of the locking device;

Figure 4 is a plan view of the same;

Figure 5 is a section on the line 5—5 of Fig. 4; and

Figure 6 is a section on the line 6—6 of 60 Fig. 5.

Referring now to the drawing, the numerals 1, 2 indicate the main line rails, and the numerals 3, 4, the switch rails, the main line rails having the switch point 5. The 65 switch rails are connected together as usual by tie-rods 6 and the switch rail 4 and switch point 5 are connected toward their outer ends by an actuating rod 7 which extends on one side of the track to a switch-stand 8, of 70 the usual construction, having a lever 9 adapted to be lifted and turned to move the switch through the actuating bar 7. Adjacent to the end of the switch point, and preferably between two cross-ties 10, I sink in 75 the road-bed endwise a section of cross-tie 11 which is adapted to support the fixed member of my locking device. This locking device in its entirety will now be described.

Connecting the switch point 5 and switch 80 rail 4 between the cross-ties 10 is a tie-rod 12 which, as shown by Fig. 2, is bent downwardly at either end to project below the level of the road-bed, which is excavated to a depth of, say, half a foot, for this purpose. The supporting block 11 embedded in the road-bed as above described, is located about centrally of the excavated portion of the road-bed between the tracks, and mounted on this supporting block are two angle 85 plates each of which has a base 13 secured to the supporting block 11 by spikes 14 and an upstanding ear indicated, respectively, by the numerals 15 and 16 (Figs. 3 and 4), said ears being apertured to receive a bearing bolt 17 on which is pivotally mounted the locking member indicated generally by the numeral 18 (Fig. 3). This locking member comprises a plate 19 which is provided with a bearing at its inner end to receive the 100

bearing bolt 17 and at its outer end is provided with two locking flanges 20 and 21 extending in opposite directions therefrom. Projecting from its outer end is a handle 22 to facilitate raising and turning the locking plate. It is generally desirable to maintain the switch point 5 locked in position against the main line rail 1, and to this end, I provide on the upper side of the plate 19, as shown in Figs. 3 and 4, an apertured lug 23, the aperture in which is adapted to coincide with a corresponding aperture 24 of the ear 16 when the switch point 5 is against the main line rail 1, as shown, said apertures being adapted to receive the staple 25 of a lock 26. Mounted on the tie-rod 12 in separated relation to each other are two locking blocks 27 and 28 (Fig. 3), which are preferably secured in position on the tie-rod in the following manner:

Secured on the upper side of the tie-rod at suitable distances apart thereon are two blocks 29 and 30, the upper surface of each of which is corrugated, as indicated at 31 (Figs. 3 and 5). As the manner of mounting the two locking blocks is the same, the following description will refer to the locking block 27, shown at the left of Fig. 3.

The block 29 is secured to the tie-rod 12 by means of bolts 32 the upper ends of which are counter-sunk in the upper surface of the block, as indicated at 33. The locking block 27 has its underside corrugated, as indicated at 34, to engage in the corrugations 31 of the block 29, and is secured in adjusted position thereon by means of a bolt 35, the nut 36 of which is counter-sunk in the upper surface of the locking block 27, as indicated at 37. The body of the block 29 is provided with a slot 38 and its underside with a corresponding groove 38^a, which latter receives the head 39 of bolt 35 to permit of the locking block 27 being moved in one direction or the other on said block 29. That is to say, by loosening the nut 36 of bolt 35, the locking block 27 can be raised to free the engagement between the corrugations 31 and 34 and the block then moved to the left or right, as shown by Fig. 5, in which movement the bolt 35 will slide in the slot 38 and its head in the groove 38^a. These locking blocks, as shown by Fig. 3, are designed to be engaged by the locking flanges 20 and 21 of the locking member 18, and the adjustment of the locking blocks described is to permit of a close engagement between the locking member and said locking blocks. In the position shown, the locking member 18 has been turned to the right in Fig. 3 to cause the flange 21 thereon to engage over the end of the locking block 28, in which position the switch point 5 will be held in locked position against the main line rail 1.

Before it is possible to change the position of the switch, the operator must first remove lock 26 and turn the locking member to the

left so that it will occupy the dotted position shown in Fig. 3. When the lever 9 of the switch-stand is now operated to move the switch point 5 away from the main line rail 1, the flange 20 will slide over the upper side of locking block 27 until it falls over the end thereof to have locking engagement therewith. As shown in Figs. 3 and 5, the upper surfaces of the locking blocks 27 and 28 are inclined upwardly in an outward direction which causes the locking member to be slightly raised as the locking block 27 is moved under it by the movement of the tie-rod 12 and causes the locking member to assume the proper angle of engagement with the end of the locking block when it falls over the same, as shown at the right of Fig. 3.

In either of the locking positions of the locking member, it will be readily seen that no accident to the switch stand can possibly change the position of the switch point 5, so long as the destructive force is not great enough to destroy the integrity of the entire structure, which would seldom, if ever, be the case.

By observing Figs. 1 and 2, it will be seen that the actuating bar 12 and the locking device 18 are located below the level of the roadbed, and that the locking device is located midway between the two rails of the track. This arrangement tends to prevent any accidental injury to the locking device from contact therewith of any part of a car passing over it, and also absolutely prevents the throwing of the switch by the brakeman, until the last car of the train has passed over the switch. It frequently occurs that a brakeman, whose duty it is to change the switch, will jump from the last car of a train and throw the switch before the rear truck of the car has passed over the switch, thus causing such rear car to be derailed. It is obvious that with my construction, such action is impossible as the brakeman cannot have access to the locking member 18 until the last car on the train has passed beyond it, and, of course, he must, as explained above, lift the locking member 19 and turn it from engagement with one locking block to rest on the surface of the other before he can manipulate the switch lever 9 to shift the switch.

The construction illustrated represents the best embodiment of my invention now known to me, but I wish it understood that except as recited in the claims, I do not wish to be limited to the precise construction and arrangement of parts shown, as I contemplate that various other embodiments of the invention could be made within the scope thereof as defined in the claims.

I claim:

1. A safety appliance for railway switches comprising a pair of switch rails, a tie-rod connecting the same, a pair of blocks secured on the tie-rod, a pair of locking blocks ad-

justably mounted on said blocks, and a manually-operable locking member mounted in fixed position between the rails of the track and adapted to be turned into engagement with said locking means in the closed or open position of the switch.

2. A safety appliance for railway switches comprising a pair of switch rails, a tie-rod connecting the same, a pair of locking blocks mounted on the tie-rod and having supporting surfaces inclined outwardly in an upward direction, and a manually-operable locking member pivotally mounted in fixed position between the rails of the track and adapted to be turned into engagement with one or the other of said locking blocks to hold the switch in the open or closed position, and to be turned from said engagement to rest upon the inclined surface of the locking block not engaged, whereby when the switch is turned to its other position the locking block on which the locking member rests will slide under and raise the locking member until the latter falls by gravity off of and into engagement with the end of the locking block supporting it.

3. A safety appliance for railway switches comprising, in combination with a pair of switch rails and an actuating rod for operating the same from a switch-stand, a tie-rod connecting the switch rails and independent of said actuating rod, locking means mounted at separated points on the tie-rod, and a manually operable locking member pivotally mounted at its lower end in fixed position and having a projection on opposite sides thereof adapted to be turned into engagement with said locking means in the closed or open position of the switch.

4. A safety appliance for railway switches comprising, in combination with a pair of switch rails and an actuating rod for operating the same from a switch-stand, a tie-rod connecting the switch rails and independent of said actuating rod, a pair of locking blocks mounted at separated points on the tie-rod, and a manually operable locking member pivotally mounted at its lower end in fixed position and having projections on opposite sides thereof adapted to be turned into engagement with one or the other of said locking blocks to hold the switch in either the open or closed position.

5. A safety appliance for railway switches comprising, in combination with a pair of switch rails and an actuating rod for operating the same from a switch-stand, a tie-rod connecting the switch rails and independent of said actuating rod, locking means mounted at separated points on the tie-rod, and a manually operable locking member pivotally mounted at its lower end in fixed position between the rails of the track and having projections on opposite sides thereof adapted to be turned into engagement with

said locking means to hold the switch in either the open or closed position.

6. A safety appliance for railway switches comprising, in combination with a pair of switch rails and an actuating rod for operating the same from a switch-stand, a tie-rod connecting the switch rails and independent of said actuating rod, a pair of locking blocks mounted at separated points on the upper side of the tie-rod, and a manually operable locking member pivotally mounted at its lower end in fixed position between the rails of the track and having projections on opposite sides thereof near its outer end adapted to be turned into engagement with one or the other of said locking blocks to hold the switch in either the open or closed position.

7. A safety appliance for railway switches comprising a pair of switch rails, a tie-rod connecting the same, a pair of adjustable locking blocks mounted at separated points on the tie-rod, and a manually operable locking member pivotally mounted at its lower end in fixed position between the main rails of the track and having projections on opposite sides thereof adapted to be turned into engagement with one or the other of said locking blocks to hold the switch in either the open or closed position.

8. A safety appliance for railway switches located below the level of the road-bed and intermediate the rails of the track, comprising, in combination with a pair of switch rails, a tie-rod connecting the same, locking means mounted at separated points on the upper side of the tie-rod, and a manually operable locking member pivotally mounted at its lower end in fixed position and having projections on opposite sides thereof adapted to be turned into engagement with said locking means to hold the switch in either the open or closed position.

9. A safety appliance for railway switches comprising, in combination with a pair of switch rails, a tie-rod connecting the same and bent downward at either end to extend between its ends below the level of the road-bed, relatively fixed locking means mounted on the upper side of the tie-rod in the intermediate lowered portion thereof, a support anchored between the rails of the track and below said tie-rod, and a manually operable locking member pivotally mounted at its lower end on said support and of a length to extend above said locking means and having projections on opposite sides thereof near its outer end adapted to be turned into engagement with said locking means in either the open or closed position of the switch.

In testimony whereof, I have hereunto set my hand.

JOSEPH F. HADDOCK.
